UNITED STATES PATENT OFFICE

MICHAEL W. MCARDLE, OF CHICAGO, ILLINOIS

DESIGN FOR A BOWL FOR A FRUIT JUICE EXTRACTOR

Application filed March 14, 1932. Serial No. 43,189. Term of patent 14 years.

To all whom it may concern:

Be it known that I, MICHAEL W. MCARDLE, a citizen of the United States, residing at Chicago, in the county of Cook and State of Illinois, have invented a new, original, and ornamental Design for Bowl for a Fruit Juice Extractor, of which the following is a specification, reference being had to the accompanying drawing, forming part thereof.

In the drawing—

Figure 1 is a side elevation of a bowl for a fruit juice extractor, showing my new design, and

Fig. 2 is a front elevation thereof.

I claim:

The ornamental design for a bowl for a fruit juice extractor, substantially as shown.

MICHAEL W. MCARDLE.
